UNITED STATES PATENT OFFICE.

EDOUARD CHARLES GLARDON, OF HAMBURG, GERMANY.

JOINT BINDER.

Application filed April 9, 1923. Serial No. 630,867.

To all whom it may concern:

Be it known that I, EDOUARD CHARLES GLARDON, a citizen of the Swiss Republic, and resident of No. 8/14 Speersort, Hamburg, in the Empire of Germany, have invented new and useful Improvements Connected With Joint Binders, of which the following is a specification.

The present invention relates to improvements connected with joint binders, such as are used for binding together wooden planks, boards and the like and especially for securing the lids or covers on chests and boxes to safeguard the contents of the latter against pilfering and fraudulent access being had thereto. More particularly the invention relates to that known class of joint binders, which consists of a U-shaped safety clamp, the perforated shanks of which are to be driven into the two parts to be secured together, and of a flat barbed nail which is driven into the said two parts and through the perforations of the shanks until its head is countersunk in one of those parts, to prevent the clamp from being withdrawn without leaving evidence that it had been tampered with.

The flat nails hitherto used in connection with joint binders of the class referred to do not afford a reliable protection against the withdrawal of the clamps, for the reason that it is possible by means of special pliers or forceps to withdraw the nail, thus liberating the clamp and enabling same to be withdrawn and to be reinserted without noticeable traces.

The arrangement of barb at the two lateral edges of the flat nails, which was provided for to prevent the withdrawal of the nail, has not proven effectual in practice. In spite of these barbs it has been possible to extract the nails by means of special pliers or forceps and in consequence to withdraw the clamp and to open the box without noticeable traces.

In order to obtain a better protection against fraudulent opening of the boxes it has been proposed to provide the flat barbed nail at its head with an extension, which was weakened at its base, the weakening being carried so far, that the head extension remained strong enough to receive the blows of the hammer or other instrument used for driving home the nail, but that it was severed or torn off from the head of the nail if an attempt was made to extract the nail.

The unavoidable variations in the quality of the material employed in the manufacture of such flat barbed nails render it impossible to warrant the tearing off of the head extension in the unauthorized attempt to extract the nail, so that the protection aimed at by the weakened head extension of the nail is not effective in every case.

In order to render effective the protection aimed at by the use of the aforesaid U-shaped safety clamps and the flat barbed nails in connection therewith means must be provided by which the extraction of the nails is impossible even if special pliers or forceps are employed which are adapted to grip the nails by their head portion without noticeable traces.

According to the present invention these means consist in the combination with the flat barbed nails of a detachable head member produced separate from the nails but attached to same in such a manner that the countersunk nails are unaccessible to pliers or forceps for the unnoticeable extraction of the nails even if it has been possible to get hold of their detachable head member and extract same.

In the annexed drawing are shown, by way of example, several modes of carrying into practice this invention.

Fig. 1 is a front elevation of the improved flat barbed nail with its separately produced detachable head member ready for use in securing U-shaped safety clamps.

Fig. 2 is an edge view of Fig. 1.

Fig. 3 is a front elevation of the improved flat barbed nail with its separately produced head member detached therefrom.

Fig. 4 is a front elevation of a modified construction of the improved flat barbed nail and of its separately produced detachable head member ready for use in securing U-shaped safety clamps.

Fig. 5 is a front elevation of the improved flat barbed nail according to Fig. 4 with its separately produced head member detached therefrom.

Fig. 6 is a front elevation of another modified construction of the improved flat barbed nail and of its separately produced detachable head member ready for use in securing U-shaped safety clamps.

Fig. 7 is a front elevation of the improved flat barbed nail according to Fig. 6 with its separately produced head member detached therefrom.

Fig. 8 is a top view of the detachable head member according to Figs. 6 and 7.

Fig. 9 is a top view of the improved flat barbed nail according to Figs. 6 and 7 after the detachable head member has been removed.

Fig. 10 is a front elevation of another modified construction of the improved flat barbed nail with its separately produced detachable head member ready for use in securing U-shaped safety clamps.

Fig. 11 is a sectional detail view of a portion of a box and its lid with one of the U-shaped safety clamps and one of the improved flat barbed nails in operative position.

Referring first to Fig. 11, *d* designates the cover of a box and *e* the body of the box.

The cover is secured to the body by means of U-shaped safety clamps (only one of which is shown having a cross-head *a* and legs or shanks *b*, *c* provided with apertures. In use, the clamps are driven into the body of the box and cover and one of the nails *g* is driven through the cover *d*, shanks *b*, *c* and into the body *e* of the box.

The nail *g* corresponds in shape and dimensions to the flat barbed nails well known in connection with U-shaped safety clamps of the kind referred to.

According to the present invention the flat barbed nail *g* is provided with a separately produced head member *f*, which is detachably secured to the nail in such a manner that it is adapted to safely receive the blows of the hammer or other instrument used for driving home the nail.

In Figs. 1 to 3 the separately produced detachable head member *f* is partly split or bifurcated as clearly shown in Fig. 3 by the reference letter *f*¹. The head member *f* in its attachment to the nail *g* sits like a rider on a horse. In order to secure a firm seat, so that the blows of the hammer or other instrument used for driving home the nail do not dislodge the head member *f*, the two shanks of the latter formed by the slot or bifurcation *f*¹ are firmly closed against the shaft of the nail *g*. To this end in Fig. 3 the shaft of the nail *g* is provided in any suitable manner with a groove *g*¹ to be engaged by the lower bifurcated extremity *f*¹ of the head member *f*. It suffices to provide such a groove *g*¹ on one side of the shaft of the nail *g*, but it is obvious that a groove *g*¹ may be provided on both sides of the nail *g* if desired.

The modified construction of the improved flat barbed nail and of its separately produced detachable head member illustrated in Figs. 4 and 5 differs from the construction shown and described with reference to Figs. 1 to 3 only in regard to the seat for the detachable head member *f*, a slot *g*² being provided at the top portion

of the nail *g* which forms a saddle for a firm seat. In pushing the detachable head member *f* with its bifurcated extremity *f*¹ over the nail *g* it fills the saddle like slot *g*² and thus gains a firm seat to withstand the blows of the hammer or other instrument used for driving home the nail.

The modified construction of the improved flat barbed nail and of its separately produced detachable head member illustrated in Figs. 6 to 9 differs from the construction shown and described with reference to Figs. 1 to 5 by the employment of a wedge-shaped head member *f*, which gains a firm seat in a slot *g*³ at the top portion of the nail *g*.

According to Figs. 6 to 9 the connection between the nail *g* and the detachable head member *f* is safeguarded by guide grooves *f*² provided at the lateral edges of the head member *f*, as indicated in Fig. 8. In pushing the detachable head member *f* into the slot *g*³, the edges bordering the latter engage the guide grooves *f*². The arrangement may be reversed by providing the edges bordering the slot *g*³ with guide grooves, which are engaged by the lateral edges of the detachable head member *f* when the latter is pushed into the slot *g*³.

The several constructions illustrated and described with reference to Figs. 1 to 9 have in common the arrangement, that the connection between the nail *g* and its detachable head member *f* allows of no co-relative axial displacement of both parts in driving home the nail.

According to Fig. 10 such a co-relative axial displacement of the nail *g* and its detachable head member *f* in driving home the nail is provided for. To that purpose the slot *g*³ extends so far over the length of the nail *g*, that it is not completely filled by the detachable head member *f* in connecting same with the nail *g*.

To receive the blows of the hammer or other instrument used for driving home the nail *g* the detachable head member *f* in each of the constructions illustrated and described with reference to Figs. 1 to 10 forms an extension, which is indicated by the reference letter *h* in Figs. 1, 2, 4, 6 and 10.

Should an attempt be made with suitable pliers or forceps to extract the nail from its operative position, which is illustrated in Fig. 11, the countersunk head extension *h* may be gripped, so that in pulling the head member *f* is detached from the nail *g*, whereas the latter remains in its operative position. After the extraction of the detachable head member *f* the nail *g* rests at such a depth with its top portion, that in the attempt to reach it marked damaging of the wood results, which is clearly perceptible even on a cursory inspection of the box.

An attempt to drive the nail *g* entirely through both shanks *b*, *c* of the U-shaped clamp is condemned to failure in view of the fact that the two lateral wings *k* integral with the top portion of the nail *g* project beyond the barbs *i*, *j* and are turned out of the plane of the barbs, so that they abut against the shank *b* of the clamp as indicated in Fig. 11.

10 The construction of my improved flat barbed nail and its separately produced detachable head member illustrated and described with reference to Fig. 10 is advantageous for the reason that in the 15 attempt to drive the nail *g* entirely through both shanks *b*, *c* of the U-shaped clamp the blows of the hammer received by the head extension *h* force the head member *f* deeper into the slot *g*^a, the 20 head *g* with its wings *k* resting on the shank *b* being thereby extended and effectively prevented from passing through the shank.

The improved detachable head member *f* shown in Figs. 1 to 5 in the shape of a rider, in Figs. 6 to 10 in the shape of a wedge may be constructed to simultaneously form the wings *k* which project beyond the barbs *i*, *j* of the nail *g* and which are destined to abut against the shank *b* of the U-shaped clamp when the nail is driven home into its operative position.

I wish it to be distinctly understood that I do not limit my invention to the several 35 shapes and forms of the flat barbed nail and of its detachable head member shown in the drawing, it being obvious that various modifications in the shapes and forms may be carried out without departing from the 40 scope and spirit of my invention.

What I do claim as my invention and desire to secure by Letters Patent is:—

1. In a joint binder the combination with a U-shaped clamp, the two shanks of which 45 are perforated and adapted to enter the two members to be secured together, of a flat barbed nail adapted to be driven into the said two members and through the per-

foration of the shanks, a separately produced head member being detachably secured to the top portion of the nail for receiving the blows of a hammer or other instrument used in driving home the nail, substantially as described and for the purpose set forth.

2. In a joint binder the combination with a U-shaped clamp, the two shanks of which are perforated and adapted to enter the two members to be secured together, of a flat barbed nail adapted to be driven into the said two members and through the perforation of the shanks, a separately produced head member being detachably secured to the top portion of the nail for receiving the blows of a hammer or other instrument used in driving home the nail, said head member being wedge-shaped and gaining a firm seat at the top portion of the nail in a slot thereof, substantially as described and for the purpose set forth.

3. In a joint binder the combination with a U-shaped clamp, the two shanks of which are perforated and adapted to enter the two members to be secured together, of a flat barbed nail adapted to be driven into the said two members and through the perforation of the shanks, a separately produced head member being detachably secured to the top portion of the nail for receiving the blows of a hammer or other instrument used in driving home the nail, said head member being wedge-shaped and gaining a firm seat at the top portion of the nail in a slot thereof, the slot extending beyond the normal seat of the head member, substantially as described and for the purpose set forth.

In witness whereof I have hereunto signed my name this 19th day of March, 1923, in the presence of two subscribing 90 witnesses.

EDOUARD CHARLES GLARDON.
